INVENTOR,

Richard E. Gray,

UNITED STATES PATENT OFFICE.

RICHARD E. GRAY, OF WILLIAMSPORT, PENNSYLVANIA.

CAR-COUPING.

SPECIFICATION forming part of Letters Patent No. 289,407, dated December 4, 1883.

Application filed December 8, 1882. (No model.)

To all whom it may concern:

Be it known that I, RICHARD E. GRAY, of Williamsport, in the county of Lycoming and State of Pennsylvania, have invented certain new and useful Improvements in Car-Couplings, of which the following is a specification.

My invention relates to car-couplings of the class known as "twin" couplings, and more especially to that type thereof in which the draw-bars or draw-heads are provided with pivoted hooks to constitute the coupling devices.

My present invention is an improvement upon the car-coupling patented to me July 25, 1882, as No. 261,702.

The object of my present invention is to constitute my improved patented coupling the buffer, in addition to its coupling capacity, and to place the draft in the center of the car.

2c The subject-matter claimed is particularly recited at the close of the specification.

In the accompanying drawings, Figure 1 is a perspective view of my improved coupling; and Fig. 2 is a plan or top view of one of the draw-bars and coupling-hooks.

It is unnecessary for me to particularly describe herein all the parts of the coupling shown, as the portions not herein particularly described are fully shown and described in my aforesaid Letters Patent, to which I hereby refer for a full description of the parts not here described. I will content myself in this specification with a description sufficient to enable my present improvements to be understood.

35 The draw-bars A of the twin-coupling are secured beneath the cars, preferably by means of metal straps B, which permit slight endwise movement of the draw-bars without lateral play. The rear ends of the draw-bars are firmly connected to the usual draft-bars or rear sections, C, of the draw-bars, which are also secured beneath the cars, as usual—for instance, by suitable metallic straps and bolts—40 so as to have slight endwise play with their bars A. Strong buffer-springs D are fitted to or in said draft-bars C, as usual, so as to ease the jar when the cars come together to be coupled. The draw-bars A and rear sections, 45 C, thereof are secured centrally beneath the cars, so as to place the draft at the center thereof.

To the front ends of the draw-bars A are pivoted the hooks E E, which constitute the coupling devices proper. The reduced shanks 55 e of said pivoted hooks are fitted in recesses in the draw-bars A, and are adapted to be rigidly locked therein in their coupling position by means of simple coupling-pins F, as fully described in my aforesaid patent.

My invention relates to car-couplings of the class known as "twin" couplings, and more especially to that type thereof in which the draw-bars or draw-heads are provided with pivoted hooks to constitute the coupling devices.

My present invention is an improvement upon the car-coupling patented to me July 25, 1882, as No. 261,702.

The object of my present invention is to constitute my improved patented coupling the buffer, in addition to its coupling capacity, and to place the draft in the center of the car.

2c The subject-matter claimed is particularly recited at the close of the specification.

In the accompanying drawings, Figure 1 is a perspective view of my improved coupling; and Fig. 2 is a plan or top view of one of the draw-bars and coupling-hooks.

It is unnecessary for me to particularly describe herein all the parts of the coupling shown, as the portions not herein particularly described are fully shown and described in my aforesaid Letters Patent, to which I hereby refer for a full description of the parts not here described. I will content myself in this specification with a description sufficient to enable my present improvements to be understood.

35 The draw-bars A of the twin-coupling are secured beneath the cars, preferably by means of metal straps B, which permit slight endwise movement of the draw-bars without lateral play. The rear ends of the draw-bars are firmly connected to the usual draft-bars or rear sections, C, of the draw-bars, which are also secured beneath the cars, as usual—for instance, by suitable metallic straps and bolts—40 so as to have slight endwise play with their bars A. Strong buffer-springs D are fitted to or in said draft-bars C, as usual, so as to ease the jar when the cars come together to be coupled. The draw-bars A and rear sections, 45 C, thereof are secured centrally beneath the cars, so as to place the draft at the center thereof.

46 The draw-bars A are pivoted to the draw-heads, and on top of said draw-heads, are cast or fastened transverse ribs or flanges a, which, when the cars are brought together, with the coupling-hooks in buffering contact, abut against the end sills, I, of the cars and prevent the draw-heads from being driven back beneath the cars.

It will thus be seen that by the organization 95 now shown the coupling-hooks constitute the buffering devices, as well as the coupling devices, in connection with the buffering-ribs a above described, while the draw-bars are given slight endwise movement for the purpose of easing 100 the jars by means of the buffering-springs already mentioned. The coupling-hooks also,

by reason of their curved front ends or faces, are caused to fit snugly into the curved re-

cesses of the draw-heads, and thereby insure the proper action upon the coupling-hook shanks and upon the safety-latches G to cause the coupling connection. As before stated, 5 the draw-bars A are capable of moving endwise in their central guides or fastenings beneath the car-bodies, while having no lateral or sidewise play.

Having thus described my improvements, I 10 claim herein—

The combination, in a twin coupling, of the draw-bars, the curved end-pivoted hook-couplings thereof, the connections which secure said draw-bars centrally beneath the cars, so 15 as to move endwise but not laterally, the curved buffer-seats in the front ends of said draw-bars,

and the ribs or flanges of said draw-bars, adapted to come against the end sills of the cars when the draw-heads are driven backward on the coming together of the cars, substantially as described, whereby the coupling-hook of one coupling fits the curved seat in the other and acts as a buffer, while the shank of the opposite coupling-hook is forced completely back into its seat, so as to insure the 25 coupling operation.

In testimony whereof I have hereunto subscribed my name.

RICHARD E. GRAY.
